UNITED STATES PATENT OFFICE.

GUST HARMOUTH, OF YALE, OKLAHOMA.

COIN CARD.

Application filed February 10, 1927. Serial No. 167,339.

This invention relates to cards for holding coins, or other similar objects, so that they can be transmitted through the mail; and it consists of a pair of cards secured together and provided with slots which overlap each other crosswise, as hereinafter fully described and claimed.

In the drawings, Figure 1 is a front view of a coin card constructed according to this invention, a portion of one card being shown removed to expose the inner surface of the other card. Fig. 2 is a cross-section through the coin card, taken on the line 2—2 in Fig. 1.

The coin card is formed of two superposed cards 5 and 7. The card 5 is provided with a series of slots 6 arranged in pairs, the slots of each pair are parallel to each other, and they are of various lengths, and are arranged at various distances apart, to suit coins of different size.

The card 7 is provided with pairs of slots 8, similar to the slots 6; and the slots 8 are arranged crosswise of the slots 6, so that coins, indicated by the dotted circles 9, can be held in the spaces between the

portions of the cards between the pairs of slots. The two cards 5 and 7 are secured together at their edges, and at other predetermined points by adhesive material 10, or they can be secured together by any other approved means. The coins can be inserted from either side of the coin card through any one of the slots, and they are held in the spaces provided for them, so that the coins can be transmitted through the mail.

What I claim is:

1. A coin card, comprising two similar superposed cards secured together at predetermined points, each card being provided with slots arranged in pairs, the pairs of slots of one card being arranged crosswise of and overlapping the pairs of slots of the other card to form spaces for the coins.

2. A coin card as set forth in claim 1, the two cards being secured together around their edges and at predetermined intervening points by adhesive material.

In testimony whereof I have affixed my signature.

GUST HARMOUTH.
